UNITED STATES PATENT OFFICE.

LEE S. CHADWICK, OF EAST CLEVELAND, OHIO, ASSIGNOR TO THE CLEVELAND METAL PRODUCTS COMPANY, OF CLEVELAND, OHIO, A CORPORATION OF OHIO.

WATER-HEATER.

1,318,355.

Specification of Letters Patent. Patented Oct. 14, 1919.

Application filed November 8, 1915. Serial No. 60,235.

To all whom it may concern:

Be it known that I, LEE S. CHADWICK, a citizen of the United States, residing at East Cleveland, in the county of Cuyahoga and State of Ohio, have invented a certain new and useful Improvement in Water-Heaters, of which the following is a full, clear, and exact description, reference being had to the accompanying drawings.

This invention relates to improvements in water-heaters, especially of the variety involving hydro-carbon burners; and the invention has for its objects the economical production of a water heater, particularly of the above mentioned class, that is highly efficient; comparatively simple of construction; and which may be thoroughly and easily cleaned.

To the ends of simplicity and cheapness, I propose to use sheet metal, principally, for the construction of the apparatus, and to employ, as far as practicable, elements that have become standard in the art; such for instance, as the particular type of burner employed, as well as the fuel supply and distributing system, and water circulating device. Also I have designed the casing which incloses the water circulating device so that one side may be conveniently and entirely opened to reveal the whole interior of the apparatus, thereby to facilitate inspection and cleaning. As is more or less common in apparatus of this character, the casing is lagged with a non-heat-conducting material, the novel feature in this connection being the manner in which the lagging is held in place and protected. In order to acquire the maximum efficiency, I preserve the established induced draft conditions of the burner by supplying the natural draft of the flue with atmospheric air at a given elevation above the burner. By thus satisfying the natural draft of the flue from outside air, the induced draft of the burner is left undisturbed, the arrangement allowing, however, the escape of the products of combustion through the flue.

Objects in addition to those above enumerated are attained through certain structural details illustrated in the accompanying drawings and brought out in the following description. In the drawings, wherein similar reference characters are used to designate corresponding parts through the

several views, Figure 1 is a front elevation 55 of my improved water heater; Fig. 2 is a sectional front elevation thereof; Fig. 3 is a horizontal section through the heater on the line 3—3 of Fig. 2 and looking in the direction of the arrows; Fig. 4 is a vertical section on the line 4—4 of Figs. 1 and 2; Fig. 5 is a detail of the stop for holding the movable side of the heater casing in elevated or open position; Fig. 6 is a vertical transverse section through the lower portion of a 60 modified form of my heater; and Fig. 7 is a detail in perspective of the supply pipe connection with the base.

The embodiment of my invention illustrated in Figs. 1 to 5 comprises a cylindrical casing 1, preferably of sheet metal, that is made up of a stationary rear side 1^a and a movable front side 1^b, the stationary side having secured to its upper end a circular cover 2, and to its lower end, a ring 3. The casing is preferably lagged with a non-heat conducting material as will be presently explained. The cover has a right angle peripheral flange 2^a within which the upper end of the side 1^a reposes and to which it is 70 attached by fastening means, such as bolts 4. The enlarged upper end of the ring 3 constitutes a flange 3^a into which the lower end of the side 1^a of the casing is inserted and to which it is attached by fastening means, such as rivets 5. Lagging 6, in the form of a sheet of asbestos, lines the inner surface of the stationary side 1^a of the casing, and the vertical edges of the side 1^a are 75 turned radially outward and then directly 80 back upon themselves to form vertically disposed lips 7 that extend from bottom to top 85 of the casing (as clearly illustrated in Fig. 2), the extreme edges of the side 1^a being 90 then bent inward and against the lagging 6, 95 thus incasing the edge of the lagging and protecting it from injury. As already explained, a sheet of asbestos is found suitable 100 for this lagging, and, as is well known to those who are familiar with the nature of this material, the same is more liable to injury at its edges than throughout its body portion. Therefore, if the edges are 105 thoroughly protected it is reasonably safe against injury. The construction thus described thoroughly protects the edges of the lagging or asbestos lining. This construction is clearly illustrated in Fig. 3.

From Figs. 3 and 4 it will also be seen that the vertical edges of the movable front side 1^b of the casing are bent outward and radially inward to form channels 10 for co-operation with the lips 7 of the rear side of the casing. This movable side is provided with lagging 11, which may comprise a sheet of asbestos, the same being thoroughly protected throughout its entire area by a liner plate 12, of substantially the same shape as the side 1^b, and having its vertical edges crimped about the corresponding edges of the lagging. It is found preferable to thus protect the inner surface of the lagging of the cover 2, for, besides this cover being movable, it may be entirely removed when occasion requires at which time it would be liable to injury because of the fact that the interior of the movable side is so thoroughly exposed. As this description proceeds, it will be found that this is not true of the stationary side of the casing, for the lagging of this side of the casing is always protected by the water circulating device. The upper end of the plate 12 which comprises the body portion of the movable side 1^b is turned inward in a position to overlie the adjacent edge of the cover 2, when said side is in its normal position; and the lower end of the plate is bent inward and then downward to repose within the flange 3^a of the ring 3. Adjacent its lower end, the movable side of the casing has an opening 15 over which a frame 16 is fitted and is attached by bolts 17 to the side 1^b, the frame having a door 18 hinged to it, said door being provided with transparent panels of mica or the like. Immediately above the door, the movable side is provided with a handle 20 whereby the side may be raised. For the purpose of retaining the side elevated when desired I provide a stop shown in detail in Fig. 5 and comprising an angle plate 21, pivoted at 22 to the side 1^a, the plate having its upper end turned laterally at 23 so that it may form a substantial abutment for the movable side when turned into the path thereof, as shown in said Fig. 5. The bolts 17 which hold the frame 16 in place, serve also to hold the lagging 11 and liner 12 to the side 1^b, and a rivet 24 performs the same function, adjacent the upper end of the movable side.

As previously mentioned, and as shown in Figs. 2 and 4, the upper end of the ring 3 is enlarged to form the flange 3^a, and the lower end of the ring is reduced to provide a neck 3^b. The upper end of a semi-frusto-conical shell 25 is attached to the body portion of the ring 3, as by rivets 26, and at its lower end the shell is flared outward into a horizontal plane to produce a flange 27 to which is attached a member 28 that is preferably in the form of a circular plate, the edge of which is flared upwardly and outwardly as shown at 29, to produce a pan.

The fuel supply and distributing system employed in my present invention is of the type disclosed in my Patent No. 1,137,574 issued April 27, 1915, and in its present embodiment comprises a distributing receptacle 30 that is supported at its upper end by means of a bracket 31, attached to the upper end of the shell 25 and the body portion of the ring 3, and at its lower end, by means of the strap 32, attached to the adjacent edge of the member or pan 28. Hinged at 33 to the front side of the distributing receptacle 30, is a carrier 34 which may be swung from an inverted position above the distributing receptacle, through almost 180° to nearly a vertical position in front of the distributing receptacle, an abutment 35 of the carrier engaging a stop 36 that is attached to the front side of the member or pan 28, to hold the carrier in such position. In this position, the carrier may receive a dispensing receptacle 37, in the shape of a bottle having a spring closed valve 38 fitted within its mouth, and said dispensing receptacle, with the carrier, may be swung to inverted position to cause the dispensing receptacle to assume the position illustrated in Fig. 2, where the stem of its valve 38 is shown as engaging the bottom of the distributing receptacle to unseat the valve and permit the contents of the dispensing receptacle to flow into the distributing receptacle until the liquid level therein forms a seal to prevent further dispensation of the liquid, until the level of the liquid is lowered through consumption.

One end of a supply pipe 40 is threaded into a hollow boss 41 that extends from the side of the distributing receptacle nearest the shell 25, and said pipe is inclined downward from such boss into the side of the shell through a notch 42, and thence horizontally through a similar notch 43 (Fig. 7) that is formed in the opposite side of the shell. The pipe is attached to the shell by having perforated plates 44 slipped lengthwise over the pipe before it is placed in position, and secured to the adjacent portions of the shell, by bolts 45. The end of the pipe 40 opposite the distributing receptacle 30 is closed by a cap 46. A burner 47, of the same general type as that shown in the patent to Jeavons No. 951,612, dated Mar. 8, 1910, is attached to the pipe 40 central within the shell 25, the same being communicatively connected to the pipe through the elbow 48, in a manner illustrated in the aforesaid Jeavons patent. The outwardly flared lower end of the gallery 49 of the burner repose within the neck 3^b of the ring 3, leaving sufficient space between the adjacent portions of the neck and gallery to allow the admission of air in sufficient quantity to maintain proper draft conditions within the casing 1. To the cover 2 of the casing is attached, by means of the clips 50, a flue connection 130

51, directly above an outlet opening 52. At some distance above the top of the casing the flue connection is provided with a series of perforations 53 for the purpose of supporting the natural draft of the flue with atmospheric air. By this means, the natural draft of the flue is supplied with outside air, leaving undisturbed the drafts induced within the casing 1 by the heat rising from the burner 47. Without the openings 53, undue suction would be created within the casing by the natural draft of the flue plus the induced draft, and this would unbalance the established draft conditions of the burner so as to impair its operation and reduce efficiency of the apparatus by too rapidly drawing the products of combustion through the casing and thereby not permitting them to expend the full amount of their heat upon the water circulating device.

The water circulating device comprises an inlet manifold 55 and an outlet manifold 56 that are connected by a series of circulating elements or coils 57, preferably formed of copper tubing. The circulating device constitutes no part of my invention, but the form illustrated herein is found highly efficient and especially well adapted to my invention. The rear end of the inlet manifold 55 is provided with an enlargement 58, having flattened sides 59 that are ordinarily intended for the application of a wrench for holding the manifold against twisting when applying a nut 60 to the threaded end 61 of the manifold, which projects through an aperture in the casing, the nut 60 acting with the enlargement 58 to squarely clamp the device in place. The design of my casing makes the use of a wrench for the purpose aforesaid extremely inconvenient if not impossible. To perform the function of the wrench, I employ a plate 62 that is secured, as by rivets 63, to the side 1^a of the casing, the plate having an aperture which aligns with the aperture of the casing through which the end 61 of the manifold extends. On each side of the enlargement 58, the plate is beaded at 64 for co-operation with one of the flattened sides 59 of the aforesaid enlargement. When thus confined between the beads 64, the enlargement 58 and manifold 55 are effectually held against turning. An ingress pipe 65, suggested by dot-and-dash lines in Fig. 4, may be attached to the internally threaded end 61 of the inlet manifold.

The outlet manifold 56 of the circulating device has an upwardly extending shank 66 that projects through an aperture 67 in the cover 2, the protruding end of the shank being threaded for the application of a nut 68, for the obvious purpose of clamping the manifold to the casing. The egress pipe

69, shown in dot-and-dash lines, may be attached to the outlet manifold. This manifold may be held against turning by a bracket that depends from the cover 2 and comprises a strap 70, formed somewhat in the shape of a V, and to the bottom of which is secured the central portion of a strap 71, the ends of which are bent downward to embrace the sides of the manifold.

In use, the water heater may be supported by the pipes 65 and 69, the entire apparatus being light enough in weight to permit of such support.

In Fig. 6 I have illustrated a modified form of my invention involving a burner of a different type than that shown in connection with the former embodiment, the present burner being designated 75. This type of burner involves commingling tubes 76 that are inclosed within a drum 77, the commingling tubes and drum being connected by rods 78. This style of burner is fully disclosed in my copending application Serial Number 49,405, filed Sept. 7, 1915. In other respects, this form of my invention is practically the same as the one above described, the only essential differences besides the burner being the lengthening of the semi-frusto-conical shell designated 25^a in this modification, in order to accommodate the commingling tubes and drum, and the omission of the door from the movable side of the casing, such being unnecessary with the present style burner. It will be observed, also, that a modified form of the ring attached to the lower end of the casing is employed in connection with this form of my invention, the same being shown at 3^c. The unchanged parts of the apparatus are referred to by the same reference numerals as are applied to the corresponding parts of the other form of my invention.

Having thus described my invention, what I claim is:

1. In a water heater, the combination of a casing comprising a substantially semi-cylindrical stationary sheet metal shell, a correspondingly shaped movable sheet metal shell, a sheet of lagging material substantially co-extensive with and covering the inner surface of the stationary shell, each lateral edge of the stationary shell being turned radially outward and then back upon itself and over the adjacent edge of the lagging material, the lateral edges of the movable shell being turned outward and then inward to embrace the edges of the stationary shell and form therewith a slidable connection, a sheet metal liner for the movable shell, a sheet of lagging material between the liner and shell, the vertical edges of the liner being crimped about the corresponding edges of the lagging, means for attaching together the liner, the lagging and the shell, a water circulating device within the

casing, and a heating device located in operative relation to the water circulating device.

2. In a water heater, the combination of 5 a casing comprising a substantially semi-cylindrical stationary side, and a correspondingly shaped movable side, a water circulating device within the casing, said device involving an inlet manifold having 10 an extension and a wrench receiving portion adjacent thereto, the casing having an aperture through which said extension projects, a plate attached to the casing adjacent said aperture and having a portion 15 for coöperation with the wrench receiving portion of the manifold thereby to prevent the manifold turning, and a heating device located in operative relation to the water circulating device.

20 3. In a water heater, the combination of a casing comprising a substantially semi-cylindrical stationary side, and a correspondingly shaped movable side, a water circulating device within the casing, said 25 device involving an inlet manifold having an extension and a wrench receiving portion adjacent thereto, the casing having an aperture through which said extension projects, a plate secured to the casing and having 30 an aperture which is arranged to align with the aperture of the casing and having opposed beads for coöperation with opposed sides of the wrench receiving portion of the manifold, and a heating device located in 35 operative relation to the water circulating device.

4. In a water heater, the combination of 40 a casing, a water circulating device therein, an open sided shell attached to and extending downward from the lower end of the casing, the opposed edges of the shell being notched, a fuel supply and distributing system supported adjacent the shell, a supply

pipe extending from the system and through the notches of the shell, perforated plates 45 through which the pipe extends, said plates being secured to the shell across the aforesaid notches, and a burner communicatively connected to the pipe substantially centrally within the shell.

5. In a water heater, the combination of a substantially cylindrical casing, a water circulating device therein, a semi-frusto-conical shell attached to and extending downward and outward from the lower end of 55 the casing, the opposed edges of the shell being notched, a pan attached to the bottom of the shell, a fuel supply and distributing system supported adjacent the shell, a supply pipe extending from the system and 60 through the notches of the shell, perforated plates through which the pipe extends, said plates being secured to the shell across the aforesaid notches, and a burner communicatively connected to the pipe substantially 65 centrally within the shell.

6. In a water heater, the combination of a casing having a neck at its lower end, a base member whereby the neck is received and the casing is supported, a supply pipe 70 extending through the opposed sides of the base and supported thereby, a fuel reservoir communicatively connected to the pipe alongside said base, a water circulating element within the casing, and a burner communicatively connected to the supply pipe within the base and arranged to discharge 75 its products of combustion into the casing through the aforesaid neck.

In testimony whereof, I hereunto affix my 80 signature in the presence of two witnesses.

LEE S. CHADWICK.
